UNITED STATES PATENT OFFICE.

MINNIE A. SAXTON, OF WASHINGTON, DISTRICT OF COLUMBIA.

DESIGN FOR A DOLL.

49,400.

Specification for Design.

Patented July 18, 1916.

Application filed March 25, 1916. Serial No. 86,822. Term of patent 7 years.

To all whom it may concern:

Be it known that I, MINNIE A. SAXTON, a citizen of the United States, residing at Washington, in the District of Columbia, have invented a new, original, and ornamental Design for Dolls, of which the following is a specification, reference being had to the accompanying drawings, forming a part thereof.

In said drawings, Figure 1 is a face or front view of the doll illustrating my new design, and Fig. 2 is a rear view of the same.

As shown, the body of the doll is covered with any suitable material in imitation of a rabbit's fur, and is provided with a head having a child's face; said head being cov-

ered by a cap or hood of the same material as the body, surmounted by vertically projecting ears resembling those of a rabbit.

The doll is ordinarily adapted to children's use as a toy.

I claim:

The ornamental design for a doll, substantially as shown and described.

In testimony whereof I have signed my name in the presence of two subscribing witnesses.

MINNIE A. SAXTON.

Witnesses:

BENJAMIN B. DOWELL,
CARRIE S. HALL.
